STAPLING PLIERS

Filed July 10, 1939

UNITED STATES PATENT OFFICE

2,251,917

STAPLING PLIERS

Stephen A. Crosby, Jackson Heights, N. Y., assignor to Speed Products Company, Long Island City, N. Y.

Application July 10, 1939, Serial No. 283,691

8 Claims. (Cl. 1—49)

The invention deals with the art of stapling machines, featuring however, a stapling machine of the type known in the art as a plier having a staple carrying and staple ejecting arm pivotally interposed between a pair of conveniently controlled upper and lower manipulatable pivoted jaws adapted to actuate a reciprocable staple ejecting plunger operatively connected to the upper jaw and movably guided in the arm for driving a staple through the material to be stapled but against a staple clinching anvil carried by the lower jaw. One object of the invention however is directly concerned with novel rotatable latch clearing means rotatably straddling the sides of the lower jaw and resiliently mounted therein and having a rotatable cradle including means adapted to be disconnectably engageable with the staple carrying and staple ejecting arm and particularly the magazine of the latter whereby the magazine and lower jaw provide a predetermined gap in the normally raised position of the arm to permit the insertion into the gap of sheet material to be stapled or fastened together. Another object of the invention is realized in the provision of a complementary connection between the upper jaw and the upper part of the blade of the staple ejecting plunger to permit the latter to move rearwardly relative to the upper pivoted jaw during downwardly slidably rectilinear displacement of the plunger and to move forwardly relative to the upper jaw upon pivotal retraction of the latter and upon rectilinear upward retraction of the slidable plunger. Other functional and structural aspects, objects, features, and advantages of the invention will be readily appreciated and understood from the following detailed specification considered with the teachings of the accompanying drawing wherein:

Fig. 1 is a perspective view of the plier according to my invention showing the staple carrying arm and the upper jaw in their normal elevated positions in respect to the lower jaw.

Fig. 2 is a view similar to Fig. 1 illustrating the related positioning of the upper jaw against plunger and the anvil of the lower jaw in operative alignment with the staple carrying and staple ejecting arm however preparatory to a complete downward stroke on the part of the plunger.

Fig. 2a is a fragmentary view of the plier showing the relation of the upper jaw in respect to the staple carrying and staple ejecting arm when the upper jaw is fully closed or depressed.

- Fig. 3 illustrates in perspective an open view of the plier.
- Fig. 4 is a vertical longitudinal and elevational view in section of the plier.
- 5 Fig. 5 is a vertical sectional view on the line 5—5 of Fig. 4.
- Fig. 6 is a horizontal sectional view on the line 6—6 of Fig. 4.
- Fig. 7 is a fragmentary sectional view of the 10 clearing latch at a time when it is rotated to be withdrawn from engagement with the magazine.
- Fig. 8 is a perspective view of the clearing latch mounted on the free end of the leaf spring seat.
- 15 15 Fig. 9 is a sectional view on the line 9—9 of Fig. 4, and
- Fig. 10 is a perspective view of the slidable latch for interlocking the magazine and cover of the staple carrying arm.
- 20 The plier P has a staple carrying and staple ejecting arm A pivotally interposed between and straddled by upper and lower jaws or handles U and L having their rear ends provided with ears 10 and 11 pivoted on the fulcrum pin 13 which also pivotally or rotatably sustains the 25 rear part of arm A defined by the rear part 14 of the magazine cover generally denoted C and the rear part 15 of the magazine M adapted to telescopically receive rear part 14.
- 30 Slidably and vertically guided at the front part of the pivoted arm A is a U shaped plunger generally designated 16 fixedly carrying the staple ejecting blade 17 adapted to drive the foremost staple 18 of a staple strip 19 through the vertical raceway 21 defined by the front wall 22 of the magazine M and the front wall 23 of fixed U shaped rail 24 forming a part of the pivoted magazine which has a bottom wall 25 provided with substantially T shaped opening 26 having 35 the expanded portion 27 communicating with the contracted portion 28 and characterizing spaced lips or shoulders 29 adapted to contact and actuate the inclined head 30 having shoulders 31 integral with a reduced stem 32 of clearing latch generally denoted 33 comprising the rotatable U shaped yoke or cradle 34 which is integral with stem 32 and with the forwardly extending fingers or projections 34' characterizing with the tail 35 of stem 32, means for retaining 40 the upwardly and forwardly extending inclined or offset rear portion or seat 35' forming a part of a leaf spring 36 having its forward end anchored to the intermediate part of the lower jaw or member L.
- 45 50 55 Operatively interconnecting plunger 16 and

the upper wall 37 of the swingable cover C is a helicoidal spring 38 which has its upper end anchored to a fixed extension 39 of wall 37 and has its lower end anchored to a lug 40 projecting from the movable plunger 16. Thus spring 38 normally holds the plunger elevated and in such relation stop means 41 of the sides of the plunger abut the fixed wall 37.

A staple follower F of the type disclosed in my copending application, S. N. 248,331, filed December 29, 1938, is slidably mounted on and interlocks with the rail 24. This follower is normally urged forwardly and against the staple strip 19 when the cover C is in a closed relation with the magazine (Fig. 1) due to the action of the looped helicoidal spring 43 having its intermediate part trained over the locking latch 44 slidably guided in slots 45 of the cover C and receivable in the notches 46 of the spaced wings 47 of the magazine. More particularly, latch 44 is provided with the curved and grooved bearing 48 adapted to receive a part of spring 43 which has its upper reach 49 anchored to a fixed lug 50 extending inwardly from the cover C and has its lower reach 51 connected to a hook or projection 52 integral with the slidable follower F. The action of spring 43 is dual in nature in that it automatically shifts latch 44 to interlock with the magazine when the cover is closed and at the same time automatically shifts the follower forwardly against the staple strip but when the cover is swung open the follower is automatically shifted rearwardly along the rail to permit the insertion of the staples in the magazine.

In instances where it is desired to employ the lower jaw L and particularly the fixed anvil 54 thereof for clinching the driven staples, the swingable lower jaw is in the position shown in Fig. 4, namely, the neck 55 of the stem 32 which extends above the horizontal arms 56 of the yoke 34 is within the contracted recess or opening 28 in the lower wall 25 of the magazine and lips or engaging means 29 of the latter are in the gaps 57 defined by shoulders 31 and the laterally extending arms 56 and since the inclined end or seat 35 of flat spring 36 continuously exerts an upwardly directed force against the forwardly extending fingers 34', yoke 34 is therefore normally urged counter clockwise in that arms 56 may be rotated partly in rectangular shaped slots 57' in the vertical sides of the lower jaw. The sides of the slots 57' however limit rotational displacement of arms 56 approximately to the extent of forty-five degrees away from the vertical axis of the slots or openings 57' when the clearing latch 33 is interlocked with the lower wall of the magazine. The arms 56 of the cradle are rotated in a counter clockwise direction to unlock the clearing latch and this is accomplished by manipulating crank or handle 60 extending upwardly from one of the arms 56. This crank together with extension 61 of the yoke or cradle 34 straddle ears 11 of the lower jaw L while arms 56 although rotatable in slots 57' of this jaw, and the slots 57' also act as a guide for bodily vertical displacement of the cradle.

With the arms 56 of the cradle, and shoulders 31 of the head 38 of the clearing latch, straddling stop lips 29, the clearing latch may be said to be interlocked with the magazine and yieldingly held in such relation by the leaf spring 36 in which event the lower part or tail part 35 of stem 32 is abutting against stop lug 63 struck out of

the lower jaw. It follows that in the interlocked relation of the clearing latch and magazine, the stem 32 is in a substantially vertical position although the magazine of arm A is held a predetermined distance from the lower jaw whereby papers or the like to be stapled may be conveniently interposed between anvil 54 and the magazine for receiving a staple ejected by blade 17 of course when both of the upper and lower jaws have been moved towards each other upon the application of finger pressure thereon in which event the upper jaw actuated the plunger but during this time the shoulders or spaced lips 29 of the magazine abut arms 56 thus causing the clearing latch 33 to be downwardly and vertically displaced but against the resistance of the inclined terminal of the flat spring 36. However upon removal of the finger pressure applied to the jaws after the stapling operation, spring 36 releases its energy, raising lugs 34', and therefore arms 56 of the cradle automatically lift lips 29 thereby pivotally raising the magazine until terminal 35 abuts stop 63.

In case it is desired to use the plier as a tacker, the lower jaw may be readily unlocked from the magazine. In this connection, the operator merely actuates handle 60 in a counterclockwise direction as indicated by the arrow in Fig. 1. Thus the cradle is rotated and hence neck 55 is removed from the reduced opening 28 and into the enlarged opening 27 whereby head 30 may be readily withdrawn from the magazine completely. Hence the lower jaw may be swung rearwardly and a staple may be discharged from the magazine with the aid of the plunger, directly against and into material to be stapled however without the utilization of the anvil.

Having disengaged the clearing latch 33 from the magazine, these structural components may be readily interlocked again by merely swinging the lower jaw in a clockwise direction whereby the inclined head 30 first strikes lips 29 (Figs. 3 and 7), causing the clearing latch to tilt forwardly until notches 57 are in alignment with the spaced lips 29 in which case spring 36 automatically urges neck 55 of stem 35 into the contracted opening 28, thus shoulders 31 and arms 56 again interlock with the lips 29 of the magazine.

A relatively loose but movable connection is provided between the forward end of the upper jaw and the staple ejecting plunger to permit direct driving action or power to be applied to the plunger on each depression of the upper jaw. The loose connection comprises a T shaped lug 70 having its stem portion 71 integral with the forward transverse wall of the plunger 16. This stem is movably guided between the sides of the contracted part of the T shaped opening 72 at the forward part of the upper jaw and therefore when the latter is depressed (Figs. 2 and 2a) from its normally elevated position, bottom face 73 of the upper jaw ultimately strikes the upper part of the U shaped plunger 16, causing the latter to move vertically downwardly while stem 71 thereof moves further and further rearwardly into the reduced part of the T shaped opening 72 to compensate for the pivotal movement of the upper jaw until the lower face 73 of the latter strikes the upper peripheral face 74 of the front part of the casing or cover C at which time a staple has been ejected from the raceway.

Upon removal of finger pressure from the up-

per jaw, spring 38 automatically retracts the plunger until stop lugs 41 of the latter strike the upper wall 37 of the cover C in which event the upper jaw has been again elevated or retracted whereby the T shaped lug 70 has moved to be at the fore part (Fig. 1) of the T shaped slot 72, and of course the laterally extending wings 75 of lug 70 prevent disengagement of the upper jaw from the plunger 16.

Even though the clearing latch is interlocked with the cover, the latter may be swung open to expose the rail of the magazine to permit the insertion of staples in the latter. To this end, latch 44 is grasped and pulled forwardly and out of notches 46. It follows that the cover and magazine are now unlocked, and the cover may be swung away from the magazine. In the event that the plier is used as a tacker, the magazine may be opened in a similar fashion after the slideable latch has been actuated to unlock the magazine.

As many changes could be made in the above described construction and many widely different species or structural embodiments could be devised without departing from the scope thereof, it is intended that all matter hereinbefore described in the specification and illustrated in the accompanying drawing shall be interpreted as illustrative and not in a limiting sense.

I claim:

1. In a stapling machine, a staple carrying arm having engaging means, an anvil supporting member pivotally sustaining said arm and having spaced sides including transversely alined openings, a spring carried by said member, a clearing latch having a cross arm rotatably disposed in said openings and adapted to removably interlock with said engaging means and having spaced means for rotatably straddling said sides and having other means retained on said spring whereby the latter normally urges said latch in a direction to interlock with said engaging means, and movable driving means for ejecting a staple from said staple carrying arm.

2. In a stapling machine, a staple carrying arm having engaging means, an anvil supporting member movably sustaining said arm and having spaced sides including transversely alined relatively elongated openings, a spring carried by said member, a clearing latch having a cross arm rotatably and rectilinearly disposed in said openings and having spaced terminal means movably straddling said sides and having other means retained on said spring whereby the latter normally urges said latch in a direction to removably interlock with said engaging means, and driving means for ejecting a staple from said staple carrying arm.

3. In a stapling machine, a staple carrying arm having lip means, an anvil supporting member pivotally sustaining said arm and having transversely spaced sides including alined and relatively elongated openings, a leaf spring in part fixed to said member and having a free portion, a clearing latch having a cross arm rotatably and rectilinearly disposed in said openings and having notched means to disengageably interlock with said lip means and having means resiliently retained on said free portion whereby the latter normally urges said latch in a direction to allow said notched means to disengageably interlock with said lip means, and driving means for ejecting a staple from said staple carrying arm.

4. In a stapling machine, a staple carrying

arm, an anvil supporting member pivotally sustaining said arm and having spaced sides including transversely alined and relatively elongated openings, said arm having a bottom wall including an opening comprising an expanded and a reduced portion defining spaced lips, a spring carried by said member, a clearing latch having a cross arm rotatably and rectilinearly disposed in said elongated openings and including notched means to disengageably interlock with said lips and having spaced means rotatably straddling said sides and having other means seated on said spring for normally urging said latch to move in a direction to allow said notched means to interlock with said lips, and driving means for ejecting a staple from said staple carrying arm.

5. In a stapling machine, a staple carrying arm having spaced lips, an anvil supporting member pivotally sustaining said arm and having spaced sides including alined and relatively elongated non-circular openings, a spring carried by said member and having a free portion, a clearing latch having a non-circular cross arm rotatably and rectilinearly disposed in said openings and including spaced shoulders defining with said cross arm means to disengageably interlock with said lips, spaced cranks extending from said cross arm and rotatably straddling said sides, said latch having a depending stem and having forwardly extending fingers retained on said free portion, the latter normally urging said latch to move in a direction towards said lips for interlocking therewith, stop means carried by said member and cooperating with said stem to limit movement of said latch in said direction, and driving means for ejecting a staple from said staple carrying arm.

6. In a stapling machine, a staple carrying arm having lip means, an anvil supporting member pivotally sustaining said arm and including spaced sides having alined openings, a leaf spring carried by said member and having a free portion, a tilttable clearing latch having a cross arm rotatably disposed in said openings, said latch having notched means to removably interlock with said lip means and having crank means rotatably straddling said sides, fingers projecting from said latch and seated on said free portion whereby the latter normally urges said latch towards said lip means, stop means to limit tiltable movement of said latch pursuant to interlocking of said lip means and notched means, and driving means for ejecting a staple from said staple carrying arm.

7. In combination, a staple carrying arm, a rectilinearly guided staple ejecting driver carried by said arm and having an attenuated stem including a head, and an actuator pivoted relatively to said arm for operating said driver and having a wall including a slot for slidably guiding said stem to permit a portion of the latter to move rearwardly in said slot relative to said actuator upon downward displacement of said driver relative to said arm and forwardly relative to said actuator upon the retraction of said driver, said head projecting laterally of and above said slot and cooperating with said wall to limit tilting of said actuator away from said arm.

8. In combination, a staple carrying arm, a rectilinearly guided staple ejecting driver carried by said arm and having an attenuated stem including a transversely arranged cross arm, and a pivoted actuator for operating said driver and

having a wall including a substantially T shaped slot for receiving and slidably guiding said stem to permit a portion of the latter to move rearwardly in said slot relative to said actuator upon downward displacement of said driver relative to said arm and forwardly in said slot relative to said actuator upon the retraction of said driver,

5 said cross arm being disposed above said wall and extending laterally of said slot and cooperating with said wall to limit upward pivotal displacement of said actuator away from said arm.

STEPHEN A. CROSBY.
